(57) **CLAIM**

The ornamental design for an LCD writing tablet, as shown and described.

DESCRIPTION

FIG. 1 is a front perspective view of an LCD writing tablet, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of an enclosed area of the LCD writing tablet labeled 9 in FIG. 1.

The broken lines encircling portions of the LCD writing tablet illustrated in an enlargement in FIG. 9 form no part of the claimed design. All other broken lines depict portions of the LCD writing tablet that form no part of the claimed design.

1 Claim, 9 Drawing Sheets
